UNITED STATES PATENT OFFICE.

JEREMIAH H. SMITH, OF PLEASANTON, KANSAS.

SADDLE-PAD BLOCK.

SPECIFICATION forming part of Letters Patent No. 268,742, dated December 5, 1882.

Application filed October 3, 1882. (No model.)

To all whom it may concern:

Be it known that I, JEREMIAH H. SMITH, a citizen of the United States of America, residing at Pleasanton, in the county of Linn and State of Kansas, have invented certain new and useful Improvements in Saddle-Pad Blocks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in a device for stretching and stuffing the pads of harness-saddles; and it consists in the combination of two plates, which are curved longitudinally and are provided with end catches, which plates form a block upon which the covering for the pad is stretched and secured to the saddle-tree, after which the plate forming the separable block or form is removed through one end of the stretched cover and the stuffing inserted, as will be hereinafter set forth, and pointed out in the claim.

Heretofore harness-pad machines have been constructed which have been provided with what is termed an "adjustable trough," in which the leather to be formed into the pad is placed, over which leather is placed a block. This class of machines is different from my invention, which forms the leather in the proper shape upon the back of the saddle to which it is attached, and it dispenses with the extra stretching which would be required if the pads were first formed and then attached to the saddle.

In the annexed drawings, Figure 1 is a longitudinal section of a harness-saddle of ordinary construction, showing one of the pads stuffed and the other with my improved pad-blocks therein. Fig. 2 is a transverse section through the line $x-x$ on Fig. 1. Fig. 3 is a perspective view, showing the plates together forming the pad-block. Figs. 4 and 5 are perspective views of the plates detached; and Fig. 6 is a rear view of a part of the saddle plate or back, showing the leather forming the pad attached to the same.

In the annexed drawings, A represents the bed of the saddle, which is provided with a central stiffened portion or bridge and end portions, A', which extend to the end of the pad. This bed A is usually formed of solid leather, to which are attached by rivets screw-threaded sockets for the reception of the fastening-bolt and turrets. To this bed A the leather which covers the stuffing and constitutes the pad is attached in the ordinary manner, usually by tacks.

In forming the pad the leather covering B is attached to one side of the bed A, and the plates C and D are placed together, as shown in Fig. 3, and put upon the rear of the bed A, the leather B being first dampened, so as to be easily stretched. The cover B is then drawn over the forms C and D, and finally secured to the bed A at its sides, the outer end being left open for the removal of the plates. The former consists of two metallic plates, C and D, the upper one, C, being curved slightly longitudinally. This plate C is provided at its upper end with a central slot, e, and at its lower end with downwardly-projecting lug d. This plate is also provided with central depression, e, in which will fit the socket through which the turret passes. In the lower end of this plate, above the lug d, is an opening, f, in which the ends of a suitable tool may be placed for withdrawing the plate after the pad has been formed. The lower plate, D, is curved, as shown in Figs. 1 and 5, so as to conform to the shape of the lower part of the pad, and it is provided at its ends with a slot and catch, as shown. After the leather has been stretched over the plates C and D and attached to the bed A of the saddle the plates are removed, the upper one, C, being withdrawn first by placing a suitably-constructed tool in the opening f. After the other plate has been removed the lower one can be easily slid through the end opening. The stuffing is then inserted through the end opening, after which the lower portion, A', is attached to the bed. Thus the pad is formed ready for use upon the saddle-bed.

I am aware that prior to my invention blocks or formers which are separable have been provided for stretching or shaping the leather which forms the covering for the pad before it

is applied to the saddle, and I do not claim such as my invention.

Thus having described my invention, what I claim as new, and desire to secure by Letters Patent, is—

As an improved article of manufacture, the pad-block consisting of the plates C and D, provided with central slots, catches, and open-

ings e and f, substantially as shown and described.

In testimony whereof I affix my signature in presence of two witnesses.

JEREMIAH H. SMITH.
